UNITED STATES PATENT OFFICE.

CHARLES H. JOY, JR., AND LOUIS J. SAUER, OF CHICAGO, ILLINOIS, ASSIGNEES TO
CHARLES H. JOY, OF CHICAGO, ILLINOIS.

COMBINATION DOOR LOCK.

Application filed February 6, 1922. Serial No. 534,335.

To all whom it may concern:

Be it known that we, CHARLES H. JOY, Jr., and LOUIS J. SAUER, citizens of the United States, and residents of the city of Chicago, in the county of Cook and State of Illinois, have invented certain new and useful Improvements in a Combination Door Lock; and we do hereby declare that the following is a full, clear, and exact description of the same, reference being had to the accompanying drawings, and to the numerals of reference marked thereon, which form a part of this specification.

This invention relates to locks of the type in which a number of restraining parts must be correctly positioned for the lock to be operated.

It is an object of this invention to provide a lock which can be opened from one side of the door only by a person who knows the combination, but can be opened from the other side of the door by any person.

It is a further object of this invention to provide a lock in which the parts are spring-pressed toward lock operating position so that they will assume that position as soon as the combination is set up.

It is a further object of this invention to provide a lock in which the combination may be changed by shifting stoppers among a series of holes so that hole which is left unobstructed is altered.

It is a further object of this invention to provide a lock in which no indicator dial is needed but the correct positioning of the restraining parts may be obtained by counting certain clicks.

It is a further object of this invention to provide a lock in which the combination must be set up in order to open the door, but in which the act of moving the bolt to releasing position will automatically restore the restraining parts to their zero position.

It is a further object of this invention to provide a lock in which the parts that must be positioned to set up the combination can be quickly and certainly returned to their zero position if an incorrect combination is set up.

It is a further object of this invention to provide a lock in which the several parts

that must be positioned are independently operated by separate handles.

It is a further object of this invention to provide a lock in which the independently operated parts that must be positioned are returned to their zero position by a common operator.

It is a further object of this invention to provide a separable connection between each part that is to be positioned and the means for positioning it.

It is a further object of this invention to provide a stop whereby the handle for operating a part that is to be positioned may be made to make one complete revolution and stop at the end of such a revolution.

It is a further object of this invention to provide a combination lock in which the combination may be changed without the necessity of any special tools.

Other and further important objects of this invention will be apparent from the disclosures in the specification and drawings.

The invention (in a preferred form) is illustrated in the drawings and hereinafter more fully described.

On the drawings:

Figure 1 is a view of the lock from the outside of the door.

Figure 2 is a view of the lock from the inside of the door.

Figure 3 is a vertical section of the lock taken through the door.

Figure 4 is a view of the lock from the inside of the door, all of the parts between the inside of the door and the click mechanism being removed.

Figure 5 is a similar view, all of the parts between the inside of the door and the racks moved by the click mechanism being removed.

Figure 6 is a similar view, all of the parts between the inside of the door and the plate which covers the racks shown in Figure 5 being removed.

Figure 7 is a section upon the line 7-7 of Figure 3, the central shaft being removed.

Figure 8 is a view similar to Figures 4 to 6, the inner cover plate only being removed.

Figure 9 is a section upon the line 9-9 of Figure 5 on an enlarged scale.

- Figure 11 is a section upon the line 11—11 of Figure 10.
- 5 Figure 12 is a section upon the line 12—12 of Figure 3, certain parts being shown in elevation.
- Figure 13 is a detail view showing one of the racks illustrated in Figure 5.
- 10 Figure 14 is a section similar to Figure 3 but on a larger scale, showing in elevation the central portion thereof, with certain parts in the position which they occupy during unlocking movement.
- 15 Figure 15 is a development of the cam shown in Figure 14.
- Figure 16 is a view upon an enlarged scale of the plate shown in Figure 7 and the central pillar thereon.
- 20 Figure 17 is a view of the cylindrical housing for the lock.
- Figure 18 is a section upon the line 18—18 of Figure 2.
- 25 Figure 19 is a diagram to illustrate the relative position of certain parts in the lock.
- Figure 20 is a section upon the line 20—20 of Figure 14.
- Figure 21 is a section upon the line 21—21 of Figure 14.
- 30 As shown on the drawings:
- The lock is imbedded in a door 1 and includes a bolt 2, which slides in a housing 3 and is reciprocated by means of a lug 4 cooperating with a notch 5 in the bolt. The 35 lug 4 is moved by mechanism housed within a cylindrical housing 6. The end of this housing which is intended to be on the outside of the door is closed by a thimble 8 which has a flange 9 intended to lie against the surface of the door. This flange is beveled to give a good appearance to the door. The thimble contains a central recess 10 in which the base of the knob 11 can both 40 rotate and slide. Rigid with the knob 11 is the central spindle 12 which has a bearing in a bushing 13 screwed into a boss 14 that is located at the center of the thimble 8 and forms the innermost extension thereof.
- 45 In the front plate of the thimble 8 are mounted any desired number of positioning spindles 15 which are turned by heads 16. As shown on the drawings, there are four of these heads 16 and there are four combination elements to be positioned thereby, but it is obvious that a larger or smaller number of positioning spindles may be used with a corresponding number of combination elements. Each of the heads 16 is seated in a shallow recess 17 in the surface of the 50 thimble 8, as is best seen from Figure 10. The recess contains a spacing collar 18 which separates the thimble from the floor of the recess. The head 16 has a lug 19 which extends down to the floor of the recess at one side of the collar 18, and the collar has a 55 lug 20 which projects from that side of the collar away from the head 16. To accommodate the lug 20, a recess 21 is provided in the floor of the recess 17 at one side thereof. The collar 18 is also provided with a radially projecting lug 22 which contacts with the lug 19 when the head 16 is rotated.
- 60 The circumferential width of the deeper recess 21 exceeds the circumferential width of the projection 20 by an amount equal to the combined circumferential width of the lugs 19 and 22. If therefore, the head 16 is rotated clockwise as viewed in Figure 11, the lug 19 will travel away from the lug 22, and when it has completed nearly a 65 whole revolution, it will contact with the upper edge of the lug 22 and move the collar 18. The motion of the collar 18 is limited by the circumferential width of the notch 21. The lug 22 can move therefore just enough to enable the lug 19 to arrive at its initial position, that is, the head 16 can be made to make exactly one complete revolution and no more.
- 70 The spindle 15 is moved by the rotation of the head 16. The spindle has on it an enlargement 23 which is seated in a recess 24 in the head of the thimble 8. At the opening of the recess 24 is mounted a shaft 25 which ends in a pinion 26. The end of the shaft 25 nearest the recess has a click wheel 27. A similar shaft 25 with its click wheel 27 and pinion 26 is associated with each of the heads 16 and spindles 15. Each shaft 25 is connected to its spindle 15 by a spring 28. One end of this spring is fastened to the spindle 15 and the other end to the shaft 25 so that if the head 16 is turned when the shaft 25 cannot turn, the strain will be absorbed by the spring 28, and if the turning is carried far enough so that something must break, the spring 28 will break before injury is done to any of the delicate parts of the lock.
- 75 The several shafts 25 are held in place by bearings in the plate 29 which fits between the boss 14 and the housing 6 and has a flange 33 that abuts against the inner edge of the thimble 8. The space between the plate 29 and the inner face of the thimble 8 is occupied by the click wheels 27 and the parts cooperating with them which are illustrated in Figure 4. Associated with each click wheel is a pawl 30 pivoted at 31, either to the thimble 8 or to the plate 29. One end of each pawl 30 cooperates with the wheel 27 to make clicks as the wheels rotate. The other end of the pawl is bifurcated, the branches of the bifurcation being made to straddle the end of a leaf spring 32 which is anchored at 33. As the wheels 27 are rotated, their teeth push the ends of the pawls 30 causing them to tilt against the restraining effect of the springs 32 so that as a tooth passes the end of the pawl 30, the 80

pawl will swing against the next tooth, making an audible click and producing a shock which can be felt in the operator's fingers that are being used to turn the head 16. 5 Thus is it possible for the operator to know through how many teeth he turns the wheel 27 and consequently how far he has turned the pinion 26.

The pinion 26 meshes with curved racks 10 34 best illustrated in Figures 5 and 13. Each of these racks contains as many teeth as the corresponding pinion 26. The rack 34 is in each case integral with an arcuate member 36 which is connected by a separable joint with a second arcuate member 37. The second arcuate member has a flange 35 which is in line with the rack 34. When the pinion is rotated in the direction to move the flange 35 toward the pinion, the end of 20 the flange acts as a stop beyond which the pinion cannot be turned.

The connected arcuate members 36 and 37 lie in the same annular space and in the case of two pairs their outer surfaces bear 25 against the inner face of a cup 38, the floor 39 of which is fastened to the plate 29, by screws 40. The other two pairs of connected arcuate members have their inner faces against the face of a boss 41 upstanding 30 from the center of the floor 39 of the cup 38. The cover 42 of this cup has a depending flange 43 that fills the space between the outer and inner sets of connected arcuate members. This flange 43 forms with the 35 wall 38 of the cup a raceway for the outer sets of arcuate members and with the boss 41 it forms a raceway for the inner sets of connected arcuate members. As illustrated, there are two raceways to accommodate the 40 four sets of arcuate members but it is obvious that a larger number of sets can be used if desired and that if needed, a large number of raceways can be provided for them.

45 Each member 36 has a long arm 47 and a short arm 49 between which is a recess. Each member 37 has an arm 48 which when two arcuate members are connected extends into this recess. The face of the arm 49 toward the recess is concave to afford a shallow seat for a leaf spring 84 which is connected to the member 37 and extends along the side of the arm 48. The leaf spring is bowed so as to yieldingly grip the seat in 50 arm 49 and so hold the members 36 and 37 together but permit them to be separated by a slight pull.

In order to insure that the arm 48 upon the part 37 will enter the recess upon the 60 part 36, the ends of the arms 47 and 49 are rounded as shown at 51 and 50.

Each of the arcuate members 37 has a pin 46 extending upward from the end nearest the flange 35. The pins 46 project up 65 through the cover 42 and slots 52 are pro-

vided therein for their motion. The cover 42 is rotatably held in place by the enlargement 45 upon the end of the bushing 13 and during the motion of the cover if the end of one of the slots 52 contacts with its pin 46, 70 the pin will be moved. This will move the parts 37 and carry the parts 36 and therefore the racks 34 with it. This will rotate the shafts 25 and so the spindles 15 causing rotation of the heads 16 and at the same time 75 making clicks with the wheels 27. Rotation of the cover plate 42 to the position illustrated in Figure 6, brings in this way all of the pins 46 to a standard position which for convenience will be hereinafter called 80 the zero position. If the cover 42 thus moves the pins 46 when the racks 34 are already at the limit of their motion, the parts 36 and 37 will be separated by the springs 84 slipping out of the seats in arms 49. The 85 cover 42 has upstanding from it a pin 53 by which it is rotated.

The spindle 12 has a collar 54 occupying the interior of the enlarged part of the bushing 13. From this collar toward the 90 inside of the door extends along the shaft 12 a keyway 55. The inside knob 56 of the lock is the end of a hollow sleeve 57 into which the spindle 12 extends. Projecting 95 into the interior of this sleeve is a pin 58 to co-operate with the keyway 55 so that the knobs 11 and 56 are compelled to rotate together, but a telescoping motion thereof at right angles to the door is possible.

The sleeve 57 has at its inner end a plate 100 59 which is shown in detail in Figure 16. This plate is provided with a plurality of series of holes 60, each series arranged in an arc corresponding to one of the slots 52 in the cover 42. One of these holes is 105 shown at 60 in Figure 9 which also shows the T-shaped pin 61 that occupies the hole. In Figure 19, for the sake of clearness, the holes have been arranged in a straight row 110 in order that they may be shown in section, and to illustrate the relation between the location of these holes, the pin 46 and the bayonet slot and lug connection described below; this connection is shown in a developed drawing beside the row of holes. 115 In each series of holes all but one of the holes is occupied. The unoccupied hole is shown in Figure 16 as being the last hole counter-clockwise, but any selected hole may be left unoccupied. The occupied holes are 120 filled by the T-shaped pins 61. These pins each consist of a rectangular head on the side of the plate 59 shown in Figure 16, which is the side toward the head 56, and a cylindrical shank which fills the hole 60.

To adjust the lock so as to have a given combination, the holes 60 are filled with pins 61 leaving vacant one hole only in each series. The hole left vacant corresponds to the particular number of clicks 130

that must be produced at the corresponding knob 16. In order to retain the pins 61 in the holes 60, a second plate 62 is positioned over the plate 59. For convenience, in attaching the plate 62 to the plate 59 and removing it therefrom, there are secured to the plate 59 a pair of set screws 63, which work through keyhole-shaped slots 64. The pin 53 goes through the plates 59 and 62, and slots 65 and 66 are provided to receive it. When the knob 56 is rotated, the plates 59 and 62 cause the pin 53 to rotate and so move the cover 42, but in order that there may be some lost motion between the knob 56 and the cover 42, the slots 65 and 66 are somewhat longer than the diameter of the pin 53. The lost motion between the plate 59 and the cover 42 is equal to the travel of the pins 46 corresponding to one click. Since the knob 11 is keyed to the knob 56 by the pin 58 and the keyway 55, it will be obvious that the cover 42 may be moved by turning either knob. When the cover is thus moved, the ends of the slots 52 contact with the pins 46 and bring them back to their zero position.

In order to prevent the knobs from turning when the lock is not to be opened, a lug 67 is provided on the interior of the bushing 13 near the enlarged end 45 thereof. The end of the sleeve 57 which carries the plate 59 is recessed to receive the enlarged end 45 of the bushing 13. The boss 68 upstanding from the central part of this recess is furnished with cam slots to cooperate with the lug 67. The shape of these slots is shown by the developed view of this boss in Figures 15 and 19. The slot nearest the knob 56 extends completely around the circumference of the boss as shown at 69. Out of this circumferential slot 69 there opens a longitudinal slot 71, which extends to about the center of the length of the boss. The longitudinal slot 71 opens into a circumferential slot 73 which extends about a quarter of the circumference, and out of the circumferential slot 73 there goes another longitudinal slot 74 which extends to the end of the boss. Figure 19 illustrates the relative position of the slots and the holes 60 in the plate 59.

When the knob 56 is in its innermost position the lug 67 is in the slot 69 and the knob 56 may be rotated completely except as the throw of the bolt affords a stop for the rotation. When the knob 56 has been rotated to such a position that the opening 71 is opposite the lug 67, the knob 56 can be moved outward so that the lug 67 will occupy the longitudinal slot 71. The knob 56 in this position can be rotated only very slightly, the play of the lug 67 between the walls of the slot 71 limiting the rotation. If the knob 56 is moved outward a little further, the lug 67 will occupy the

circumferential slot 73. The knob 56 may then be rotated about a quarter of a revolution. When the lug 67 is in the slot 73, the knob 56 can be so rotated as to bring the lug opposite the opening of the longitudinal slot 74. When this is done, the knob 56 can be moved outward to its outermost position.

The knob 56 is spring-pressed toward its inner position by a spring 75. The inner end of this spring bears against the plate 62 and the outer end bears against the inner surface of a thimble 76 which is threaded into the inside end of the sleeve 6. The outer surface of this thimble is provided with bevelled edges 77 to give a good appearance to the door.

The lug 4 which throws the bolt 2 projects through a slot 78 in the housing 6. It is integral with an arcuate, nearly semi-circular piece 79 which rides on the interior of the housing 6 and is kept from movement longitudinally thereof by the projection of the lug 4 through the slot 78. The piece 79 is wide enough longitudinally of the housing 6 so that the plate 59 contacts with the inner surface of 79 in all longitudinal positions of the knob 56. The piece 79 extends around the plate 59 for nearly a semi-circle. Two lugs 80 project radially from the plate 59. The circumferential distance apart of these lugs is less than a semi-circle and they are situated on the side of the plate 59 away from the part 79 so that as the plate 59 is rotated there is lost motion between the lugs 80 and the end of the part 79, but if the plate 59 is rotated sufficiently to take up this lost motion, the lug 80 will contact with the end of the piece 79 and then move it and so move the lug 4 and thus throw the bolt 2. Since the bolt 2 cannot be moved except by the lug 4, and the lug 4 cannot be moved except by the part 59, it follows that normally, one of the lugs 80 rests against one end of the piece 79 so that there is always lost motion to take up before the plate 59 can move the bolt 2 in the direction opposite to its last motion.

The bolt 2 is provided with an upstanding ridge 81, which is divided by the notch 5 so that a small piece 82 in line with the ridge 81 is found at the other side of the notch 5. The ridge 81 and the piece 82 are guided by a groove 85 in the upper side of the housing 3. This groove is in line with the slot 78 which at its lowest point forms a continuation of the groove in which the ridge 81 rides.

In the operation of the lock, assuming that the door is shut and locked, the operator on the outside turns the heads 16, counting the clicks which he hears and feels until at each head the number of clicks has been made which corresponds to the combination. In order to do this, the operator must

know the combination. The rotation of a head 16 moves the corresponding rack 34 and the pin 46 so that at the end of this operation, the pin 46 is in the position corresponding to the combination, that is, it is opposite an empty one of the holes 60. Each of the heads 16 in turn is thus rotated and each pin 46 is thus brought opposite an unoccupied hole 60. During this operation, 10 the boss 68 stood with the lug 67 in the passage 71. Consequently, as soon as the combination is set up as has been described, the spring 75 forces the plate 62 and so the plate 59 and the boss 68 towards the knob 11. This will bring the groove 69 into mesh with the lug 67 so that the knob 11 can be turned.

The knob 11 is turned, the part 57 being keyed thereto rotates with it, and so rotates 20 the plate 59. This plate, by means of one of the lugs 80, moves the piece 79 around the circular housing 69 and so causes the lug 4 to move the bolt 2 to release position.

The travel of the bolt requires about a 25 quarter of a revolution but the lost motion between the lugs 80 and the ends of the piece 79 is nearly equal to another quarter of a revolution so that the whole travel of the plate 59 is nearly half a revolution. The 30 plate 59 moves the pins 46 because these pins are at this time in the holes 60. As seen in Figures 12 and 6, this motion is counter-clockwise, while retracting the bolt. At the beginning of this motion, the pins 35 46 are not in the position illustrated in Figure 6 but were displaced counter-clockwise from that position the necessary distances to correspond to the combination. During retracting the bolt, therefore, each 40 part 37 moves counter-clockwise which will carry with it the part 36 until the head 16 has turned to the end of its motion. If the retracting of the bolt moves the pin 46 still further, the part 36 will be separated from 45 the part 37, but they will be again united when the bolt is again thrown.

While the pins 46 are in the holes 60, the lug 67 is in the slot 69 and either knob 11 or 56 can be rotated in either direction 50 whenever desired. Thus the bolt can be thrown or retracted at will by an operator either on the inside or the outside of the door. When the bolt is thrown, the motion of the plates is clockwise, as seen in 55 Figures 12 and 6. The pins 46 are, as already explained, moved with the plate 59; they therefore move in a clockwise direction, first bringing the parts 37 back into contact with the parts 36 and then returning the 60 racks to the position corresponding to the combination.

When the operator desires to prevent the operation of the bolt by anyone who does not know the combination, he must first release the pins 46 from the plate 59 and then

move them relative to that plate so that they no longer stand in register with the unoccupied holes 60. To do this from the outside of the door, he first rotates the knob 11 until the slot 71 comes opposite the lug 67. By 70 exerting a pressure against the knob while turning it, the operator will know when this position is reached by the knob then yielding to the pressure. The boss 68 travels during this yielding so that the lug 67 75 goes through the slot 71 into the slot 73. Pressure on the knob 11 cannot move the boss 68 any further in, because the inner end of the knob 11 comes against the bottom of the recess 10. The knob, however, can be 80 rotated, the lug 67 then being in the slot 73. By the time the boss has turned far enough to bring the lug 67 against the right hand end (as seen in Figure 15) of the slot 73, the plate 59 will have moved enough to first 85 take up the lost motion between it and the pin 53 and then to move the cover 42 so far that the pins are brought to their zero position. The position of the parts illustrated in Figures 5 to 8 and 12 corresponds to the 90 moment when this motion along the slot 73 has reached its clockwise limit.

When it is desired to again set up the combination so that the bolt may be retracted, the knob 11 is turned until the slot 71 95 meshes with the lug 67. The spring 75 will then move the plate 59 against the ends of the pins 46 and the operator will be aware of this by finding that he cannot turn the knob in either direction. This is because the 100 lug 67 now stands in the slot 71. During this rotation of the plate 59 counter-clockwise to bring the slot 71 into play, the lost motion between the plate 59 and pin 53 is 105 taken up and then the cover 42 is moved counter-clockwise.

The motion of the cover brings the counter-clockwise ends of the slots 52 away from the pins 46. At the time the holes 60 have moved farther than the cover so that the first hole in each series, that is, the one at the clockwise end of the series, now stands on the counter-clockwise side of its pin 46 at a distance equal to the travel of that pin corresponding to one click of the wheel 27. 115 This is because of the lost motion between the plate 59 and the pin 53. A motion of the head 16 therefore sufficient to produce one click, brings a pin 46 opposite the first hole of its series. The next click brings it opposite the next hole and so on; thus the combination may be set up by counting the 120 clicks.

With the door shut and locked, an operator on the inside can open it without knowing the combination, provided the lock stands, as it normally does, with the lug 67 in the passage 71. For this purpose, the operator first pulls on the knob 56, which moves the lug from the passage 71 into the 125 130

slot 73. He can then rotate the knob 56 until the slot 74 comes into mesh with the lug 67 when a further pull will completely free the boss 68 from the lug 67. The operator can then move the bolt in either direction at will. When it is desired to return the lock to the condition where it is controlled by the combination, either the knob 56 or the knob 11 is turned until the slot 74 registers with the lug 67. The spring 75 then brings the slot 73 into register with the lug and either knob may be used to bring the slot 71 in its turn into mesh with the lug. If the pins 46 do not register with empty holes 60, the boss 68 is stopped with the lug 67 in the slot 71 and the knob cannot be turned.

If the operator on the outside of the door attempts to set the combination and moves one of the heads 16 too far, he can usually return it by rotating the head backwards to its set position. He can, also, by pushing the knob 11 in, bring the lug 67 into the circumferential groove 73. He can then rotate the plate 59 and thus the cover 42 so as to return all the pins to their starting positions. Then he can repeat his attempt to set the combination.

It is not possible to turn the knob 11 too far and so put a strain upon the pins 46, because the play of the lug 4 in the slot 78 is sufficient to stop the knob before this result can occur.

When it is desired to change the combination, the thimble 76 is unscrewed. Preferably the spring 75 is attached to 76 and is removed with it. If not, this spring is next removed. Then the head 56 is rotated so as to bring the lug 67 opposite the slot 71, if it is in the slot 69 to begin with. Next the head 56 is pulled to bring the lug 67 into the circumferential slot 73. Then the head 59 is again rotated until the lug 67 is opposite the slot 74. The head 56 can then be pulled bringing the sleeve 57 and the plates 59 and 62 out of the lock. Next, the screws 63 are loosened and the plate 62 revolved until the large ends of the keyhole slots 64 are at these screws. The plate 62 can then be lifted and if desired removed from the knob 56. This gives access to the pins 61 and those which occupy the holes it is desired to have empty are removed and inserted in the holes that were empty before. The plate 62 is then replaced and rotated so that the narrow ends of the keyhole slots are against the screws 63. This brings the slots 65 and 66 into register. The head 56 and its attached parts are then replaced in the lock and the spring 75 and thimble 76 replaced in their turn.

We are aware that numerous details of construction may be varied through a wide range without departing from the principles of this invention, and we therefore do not

purpose limiting the patent granted otherwise than necessitated by the prior art.

We claim as our invention:

1. In a lock, a lock-operating member spring-pressed toward operative position, 70 said member having a plurality of holes therein, a plurality of obstacles normally preventing said member from being moved to operative position, and means for moving said obstacles so that each obstacle may be 75 positioned opposite a hole in said member whereby the member will move under spring pressure to operative position.

2. In a lock, a cylindrical housing, a circumferential slot in said housing, a bolt 80 operating member projecting through said slot, a bolt casing at right angles to the axis of said cylinder, a groove in said bolt casing in the same plane with said slot, a bolt 85 sliding in said bolt casing, a ridge on said bolt sliding in said groove, said ridge and bolt having a notch cooperating with said member.

3. In a combination lock, a plurality of 90 obstacles, means for positioning each obstacle, each of said means including a manually rotatable head, and a stop for limiting the motion of said head to one complete revolution.

4. In a combination setting device for a 95 lock, a head, a lug on said head, a collar co-axial with said head, a lug on said collar in position to contact with the lug on said head, a second lug on said collar, a stationary bearing in which said head and collar are rotatably mounted, a recess in said bearing in which the second named lug on said collar travels, the extent of said travel being sufficient only to enable the head to complete one revolution. 100

5. In a lock, an obstacle, means for positioning said obstacle, said means including a rack, a pinion meshing with said rack, a head for turning said pinion, and means 110 cooperating with said head to limit the rotation thereof to one revolution only.

6. In a lock, an obstacle, means for positioning said obstacle, said means including a rack, a pinion meshing with said rack, a head for turning said pinion, and means 115 cooperating with said head to limit the rotation thereof to one revolution only, the number of teeth in said rack being equal to the number of teeth on said pinion.

7. In a lock, an obstacle, means for positioning said obstacle including a rack and pinion, and a separable connection between said obstacle and said rack. 120

8. In a lock, an obstacle, means for positioning said obstacle including a rack and pinion, and a separable connection between said obstacle and said rack, said separable connection including a recess in one of said members and a leaf spring on the other of said members, said leaf spring cooperat- 125

130

ing with said recess to separably hold said members together.

9. In a lock, a plurality of obstacles, a lock operating member normally held out of operative position by said obstacles, means for positioning each of said obstacles in a position to permit each said operating member to move to operative position, and means actuated by the operation of the lock for moving said obstacles out of the permissive position.

10. In a combination lock, a plurality of obstacles, each obstacle being mounted upon a member having a projecting end, a rack for each obstacle, a recessed member integral with each rack, the recess being positioned to receive said projecting end, one wall of said recess having a depression, and a spring upon said projecting end adapted to enter said depression and releasably hold said obstacle and rack together.

11. In a combination lock, a plurality of obstacles, each obstacle being mounted upon a member having a projecting end, a rack for each obstacle, a recessed member integral with each rack, the recess being positioned to receive said projecting end, one wall of said recess having a depression, and a spring upon said projecting end adapted to enter said depression and releasably hold said obstacle and rack together, said recessed member also having a projecting end, and said obstacle carrying member also having a recess adapted to receive the last named projecting end, the corners on one of said members being rounded to afford guiding means for the entrance of the projecting ends into the recesses.

12. In a lock, an obstacle, a rack for moving said obstacle, a pinion for moving said rack, the number of teeth on said pinion and on said rack being equal, a click wheel on the shaft of said pinion, the number of teeth on said click wheel being equal to the number of teeth on said pinion and rack, manually operable heads for moving said shaft, and means for limiting the motion of said heads to one revolution.

13. In a click device for the positioning means of a combination lock, a click wheel, a click pawl cooperating with said wheel, a leaf spring engaging said pawl, and an anchorage for said leaf spring, the center of said click wheel, the pivot of said pawl, the attachment of said leaf spring to said pawl, and the anchorage of said leaf spring normally standing in one straight line.

14. In a lock, a plurality of obstacles, a plurality of arcuate racks, one for each of said obstacles, said racks being arranged upon a plurality of concentric circles, and a lock operating spindle concentric with said rack.

15. In an obstacle setting device for a combination lock, a plurality of arcuate

racks, a cup-shaped container holding said racks, a cover for said container, and an annular depending flange on said cover whereby a runway for said racks is afforded between said flange and said container.

70

16. In a lock, a bolt operating member, obstacles normally holding said member out of operative position in a direction at an angle to the movement of said operating member when operating the bolt, said obstacles including a stationary lug, a grooved member movable with said operating member, the grooves in said grooved member being of a size to permit passage thereof past said lug when the grooves are properly positioned.

75

17. In a lock, an operating spindle, a sleeve slidably mounted on said spindle and constrained to rotate therewith, a stationary bearing for said sleeve, and interlocking means between said bearing and sleeve, said means including a lug and a groove.

80

18. In a lock, an operating spindle, a sleeve slidably mounted on said spindle and constrained to rotate therewith, a stationary bearing for said sleeve, and interlocking means between said bearing and sleeve, said means including a lug and a groove, said groove having circumferential portions sufficient to allow rotation of the spindle to the extent needed to operate the lock, and longitudinal portions to permit motion of the sleeve to and from operative position, the walls of said longitudinal portions of the groove cooperating with said lug to prevent rotation of the spindle during such longitudinal movement.

85

19. In a door lock, an inner handle, an outer handle, a telescoping connection between said handles whereby they are constrained to rotate together, a stationary bearing for said telescoping parts, an interlocking connection between the one of said parts connected to the inner handle and the stationary bearing, said interlocking connection including a lug and a groove, the groove containing a circumferential portion of sufficient length to permit the rotation of the handles less than that necessary for operating the lock, and longitudinal portions extending from said circumferential portion one in each direction, obstacle controlled means for preventing motion of the lug along the longitudinal portion toward the inner handle far enough for the lug to emerge from said longitudinal portion.

105

20. In a door lock, an inner handle, an outer handle, spring means for moving the inner handle toward the outer handle, a lug and bayonet slot joint between said inner handle and the stationary part of the lock, a lost motion connection between the outer handle and the inner handle, a stop for limiting the motion of the outer handle toward the inner handle, whereby by moving the

110

115

120

125

130

outer handle toward the inner handle the lug and bayonet slot connection can be operated only as far as one angle of the bayonet slot, but by operating the inner handle 5 the lug and bayonet slot connection can be completely operated.

21. In a combination lock, a plate, a series of holes in said plate, a plurality of pins occupying said holes, there being fewer pins than holes whereby certain of said holes are left vacant, a second plate covering the heads of said pins whereby removal of the pins from the holes is prevented, and detachable means for securing said second 10 plate in place.

22. In a lock, a plate, a plurality of series of holes in said plate, pins occupying said holes, the pins being fewer in number than the holes whereby certain of said holes 20 are left vacant, obstacles one for each series of holes, means for positioning the obstacles whereby they may be placed opposite the unoccupied holes, and means for displacing said obstacles from said position, said 25 last named means including a lost motion connection to the plate containing the holes.

23. In a lock, a plurality of obstacles, positioning means for said obstacles, a container housing said positioning means, a 30 plate rotatably mounted adjacent said container, said plate having arcuate slots one for each of said obstacles whereby rotating the plate to a definite position will move the obstacle to a definite position.

35. 24. In a lock, a plurality of obstacles, positioning means for said obstacles, a container housing said positioning means, a plate rotatably mounted adjacent said container, said plate having arcuate slots one 40 for each of said obstacles whereby rotating the plate to a definite position will move the obstacle to a definite position, and means actuated by the operation of the lock for moving said plate to said definite position.

45. 25. In a lock, a plurality of obstacles, separate manually operated means for positioning said obstacles, a lock operating member, spring actuated means for moving said operating member into operative position, 50 said obstacles operating to prevent said motion except when said obstacles are in permissive position, spindle actuated means for operating said operating member when in operative position, and manually operated means for actuating said spindle.

60. 26. In a lock, an operating member, adapted to actuate the lock in either of two operative positions, spring actuated means for moving said operative member to one of said operative positions, manually actuated means for moving said operative member to the other of said operative positions, and manually controlled obstacles preventing 65 said spring actuated means from moving said operative member to the corresponding

operative position except when said operative members are in permissive position.

27. In a lock, a cylindrical housing, a circumferential slot in said housing, a lug projecting through said slot, an arcuate member 70 connected with said lug contacting with the inner surface of said housing, a lock operating member actuating said arcuate member, means for restraining the lock actuating member from said actuation except in either 75 of two operative positions, obstacle controlled means for moving said operative member longitudinally of said housing into one of said operative positions, and manually controlled means for moving the operative 80 member into the other of said operating positions, said arcuate member extending longitudinally of said housing beyond each of said two positions.

28. In a door lock, an inner handle, an 85 outer handle, an operative member connected to the inner handle a telescoping connection between said two handles whereby they are constrained to rotate together, a spring pressing said operative member toward said outer handle, obstacle controlled 90 means for limiting the motion of said operative member in this direction, and means movable independently of the telescoping motion of the handles for controlling said 95 obstacles.

29. In a door lock, an inner handle, an outer handle, an operative member connected to the inner handle, a telescoping connection between said two handles whereby 100 they are constrained to rotate together, a spring pressing said operative member toward said outer handle, obstacle controlled means for limiting the motion of said operative member in this direction, means connected to the outer handle for moving the operative member in the opposite direction, a stop limiting the movement of the operative member by said outer handle, and means 105 distinct from said outer handle for positioning said stop.

30. In a lock, an operative member, means for moving said operative member into either of two lock operative positions, movable obstacles controlling the motion of said 110 operating member toward one of said positions, means for moving said obstacles by the motion of said operative member, and means preventing such action of said operative member except in the two operative positions 115 and in one intermediate position.

31. In a door lock, an inner handle, an outer handle, a telescoping connection between the handles whereby they are constrained to rotate together, a lug and bayonet 120 slot interlock between the inner handle and the stationary part of the lock, a stop on said telescoping connection whereby motion of the outer handle toward the inner handle can move the interlock, a stop on the station- 125 130

- ary part of the lock whereby motion of the outer handle toward the inner handle cannot go further than sufficient to move the bayonet slot interlock to its central position, the lost motion between the inner handle and the stop on the telescoping connection being sufficient to enable the inner handle to move the bayonet slot interlock to an extreme position.
32. In a lock, a combination setting means including a manually operated member external of the lock, a pinion internal of the lock, and a connection, capable of breaking under a stress smaller than would injure the lock, between said manually operated member and said pinion.
33. In an obstacle controlled lock, a plurality of obstacle moving devices, means for manually moving said devices, a common controlling means for moving all of said devices, and means controlled by the operation of the lock for actuating said common controlling means.
34. In a combination lock, means for determining the combination removably mounted in the lock, and means for setting the lock to correspond to said combination secured in the lock separately from said first named means whereby the combination changing means may be removed from the lock and the combination changed without disturbing the combination setting means.
35. In a lock, a plurality of pairs of cooperating means for holding said lock in inoperative condition except when said pairs are each in permissive relation, a plurality of manually operated means, one means for each pair, for bringing said pairs into permissive relation, and spring actuated means for bringing the lock into operative condition when all of said pairs are in permissive relation.
36. In a lock, a plurality of pairs of cooperating devices for preventing the lock from assuming operative condition except when said pairs are each in permissive relation, a plurality of manually actuated operative
- means, one means for each pair, for acting each upon one member of said pair for moving said pairs into permissive relation, a common actuating means for moving said pairs out of permissive relation, means for bringing the lock into operative condition when said pairs are in permissive relation, means for operating the lock when in operative condition, and means actuated by the operation of the lock for actuating said common operating means for moving said pairs out of permissive relation.
37. In a lock, a plurality of combination elements, each of which must be brought to a predetermined situation to establish the combination, means preventing the movement of the lock to release position except when the combination is established, each combination element including a step-by-step device, means associated with each combination element for changing at will the number of steps necessary to produce the predetermined situation, and a common operating means for returning all said step-by-step devices.
38. In a lock, a plurality of combination elements, each of which must be brought to a predetermined situation to establish the combination, means preventing the movement of the lock to release position except when the combination is established, each combination element including a step-by-step device, means associated with each combination element for changing at will the number of steps necessary to produce the predetermined situation, and a common operating means for returning all said step-by-step devices, said means having a lost motion equivalent to one of said steps.
- In testimony whereof we have hereunto subscribed our names in the presence of two subscribing witnesses.
